UNITED STATES PATENT OFFICE.

JOHN J. WOMPEY, OF DENVER, COLORADO.

COOLING BOX.

Application filed May 12, 1922. Serial No. 560,515.

To all whom it may concern:

Be it known that I, JOHN J. WOMPEY, a citizen of the United States, residing at Denver, in the county of Denver and State 5 of Colorado, have invented certain new and useful Improvements in Cooling Boxes, of which the following is a specification.

This invention relates to cooling boxes for the preservation of food stuff and its 10 principal object is to provide a container of this character in which simplicity of construction is combined with strength, durability and practicability in use.

Boxes made in accordance with my invention 15 may be used separately in one or more units or they may be embodied in the construction of soda fountains, refrigerators and other similar structures, it being understood that my invention is particularly 20 adapted to maintain ice cream and other confections in a frozen condition.

It is a further object of my invention to provide a box of the above stated type which is constructed without the use of nails, rivets, screws or other like fastening means and which therefore can be produced at a greatly reduced cost of manufacture, and has none of the defects often caused by broken screw or rivet heads or leaky joints.

30 An embodiment of my invention has been illustrated in the accompanying drawings in the various views of which like parts are similarly designated and in which—

Figure 1 represents a partially sectional 35 top view of a cooling box of my improved construction;

Figure 2, a vertical section taken on the line 2—2, Figure 1; and

Figure 3, an enlarged fragmentary section 40 showing the construction of the corner joints of the metal shell and lining, constituting a distinctive feature of the invention.

Referring more specifically to the drawings, my improved cooling box consists of a 45 lining structure 5 of preferably rectangular form, a similarly shaped shell 6 which constitutes the outer surface of the device, and an interposed filling 7 of suitable insulating material.

The lining and the shell are composed of metal plates which are fastened together at their edges by so called slip lock joints of a channel-and-flange type.

55 Each joint is formed by bending the adjoining edge-portions of each two sheets re-

spectively into a channel 8 and a flange 9 which interlock as shown in detail in Figure 3 of the drawings.

After the flange is placed in the channel, 60 the latter is filled with solder, and the box-shaped shell and lining are thus made air and water tight. The joints formed as shown and described furthermore reinforce the structures at their corners, and thereby 65 add to their strength and durability.

The space between the lining and shell structure is occupied by an insulating filling which in the construction shown in the drawings, is composed of a layer of cork 10, 70 a layer of wood 12 and an interposed sheet of insulating paper 13. In the bottom portion of the space, the wood layer is placed lowermost to provide a substantial base for the attachment of the short legs 14 upon 75 which the structure is supported.

The inner and outer members of the box formed and placed as shown, are connected at their upper edges by a rectangular plate 15 which covers the filling and is fastened 80 to the members by the same joints which connect the plates of which the members are composed.

A sheet metal cover 16 filled with wood or other insulating material fits inside the box 85 at the upper end thereof and is flanged for its support upon the top plate. The cover has a central opening normally closed by a flanged lid 17 which affords ready access to the interior of the receptacle.

90 A drain pipe 18 extending through a wall of the box connects with an opening in the bottom portion of the inner member thereof, for the discharge of water.

95 A lock nut 19 screwed on the pipe against the outer surface of the box, seals the opening through which it extends, against leakage, and this nut has a downwardly extending outwardly flaring lip 19^a which prevents the melting frosting on the outside of the pipe from dripping along the surface of the shell.

Having thus described my invention, what I claim and desire to secure by Letters Patent is:

105 1. A cooling box of the character described comprising inner and outer box-shaped members made of sheet metal and spaced from each other at their sides and bottoms, a sheet metal plate connecting said members at their upper edges, a movable cover closing the inner member at the top 110

of the box, and a filling of insulating material in the space between the members.

2. A cooling box of the character described comprising inner and outer box-shaped members made of sheet metal, a sheet metal plate connecting said members at their upper edges, and a filling in the space between the members, consisting of layers of wood and cork and interposed sheets of insulating paper.

3. A cooling box of the character described comprising inner and outer box-shaped members made of sheet metal and spaced from each other at their sides and bottoms, a sheet metal plate connecting said members at their upper edges, a filling of insulating material in the space between the members, including a wooden part in the bottom portion of the space, and legs for the support of the box, fastened to said wooden part.

4. A cooling box of the character described comprising inner and outer box-shaped members made of sheet metal plates connected by channel-and-flange joints, a sheet metal plate connecting the members at their upper edges, and a filling of insulating material in the space between the members.

5. A cooling box of the character described comprising inner and outer box-shaped members made of sheet metal plates connected by soldered channel-and-flange joints, a sheet metal plate connecting the members at their upper edges, and a filling of insulating material in the space between the members.

6. A cooling box of the character described comprising inner and outer box-shaped members made of sheet metal plates connected by soldered channel-and-flange joints, a sheet metal spacing plate connected at the upper edges of the members by similar joints, a movable cover closing the inner member at the top of the box, and a filling of insulating material in the space between the members.

7. In a cooling box of the character described, the combination with an insulated box structure, of a drain pipe extending through an opening thereof, and a nut on the drain pipe sealing the opening against leakage and having an outwardly flaring lip to conduct dripping moisture away from the surface of the box.

In testimony whereof I have affixed my signature.

JOHN J. WOMPEY.
